UNITED STATES PATENT OFFICE.

CHARLES E. DAVIS, OF CHICAGO, ILLINOIS, ASSIGNEE TO GOODMAN MANUFACTURING COMPANY, OF CHICAGO, ILLINOIS, A CORPORATION OF ILLINOIS.

MINING-MACHINE.

1,282,768.

Specification of Letters Patent. Patented Oct. 29, 1918.

Application filed October 6, 1916. Serial No. 585,549.

To all whom it may concern:

Be it known that I, CHARLES E. DAVIS, a citizen of the United States, residing at Chicago, in the county of Cook and State 5 of Illinois, have invented a certain new and useful Improvement in Mining-Machines, of which the following is a specification.

This invention relates to mining machines, and has for its object to provide a new and improved machine of this description.

The invention is illustrated in the accompanying drawings, wherein—

Figure 1 is a plan view of a machine embodying the invention;

Fig. 2 is a side elevation of the device shown in Fig. 1;

Fig. 3 is a sectional view taken on line 3—3 of Fig. 1;

Fig. 4 is a sectional view taken on line 4—4 of Fig. 3.

Like numerals refer to like parts throughout the several figures.

The mining machine herein shown is of the type having a forwardly projecting cutter arm 1, provided with an endless cutter chain 2, which passes around a sprocket wheel 3 at the front end of the cutter arm, and a sprocket wheel 4 at the rear end 30 thereof, and is driven by means of a motor 5. The machine is provided with a suitable frame, upon which the motor and associated parts are mounted, and the cutter arm 1 is connected with this frame. The frame normally rests upon the floor of the mine and the entire frame and cutter arm move together when the machine is in operation, said movement being produced by a cable connected with a fixed part outside of the 40 machine, as hereinafter explained. The machine is first moved longitudinally so as to make the first cut or entry into the coal, and is then moved laterally along the face of the coal. In the device shown the 45 chain is fed by means of a flexible power transmitting device 6, which passes over a drum 7 operated by the motor, and which is connected to a stationary part. When it is desired to make the first cut or entry into 50 the coal, the power transmitting device 6 is connected to a stationary part 8, arranged in such position as to cause the machine to move longitudinally when the drum is rotated. This device tends to produce a lateral movement of the cutter arm, and the

cutting parts of the chain engaging the coal also tend to produce a lateral movement of the cutter arm. In order to prevent this lateral movement I provide the cutter arm with two guides or beams 9 and 10. Between these beams there is provided a guiding device having a guiding part 11 and a shoe 12. The guiding part 11 is provided with means for fixing it in position, such, for example, as the jack 13 which is adapted to be brought into engagement with the face of the coal, or other stationary part. It will thus be seen that when the jack is tightened the guiding part 11 is held rigidly in position, the shoe 12 engaging the ground. 70 The machine can then be moved forward, but will be held against lateral movement. The part 11 is preferably inclined as shown in Fig. 4, said inclination being in the direction toward which the action of the cutters tends to move the cutter arm. It will be seen that this inclination of the arm gives the jack a greater capacity to resist lateral movement of the machine. When the machine first starts forward the guiding device will be at the front end of the cutter arm, and when the forward cut is finished, it will be at the rear end of the cutter arm. The cutter chain bears against the outer surfaces of the beams 9 and 10. Each beam 80 therefore has two bearing surfaces; one an outer bearing surface for the cutter chain, and the other an inner bearing surface for the guiding device. Such beams, therefore, have a plurality of functions. They act as 85 the frame for the cutter arm, as a guide for the cutter chain, and as a guide for the guiding device. After the forward cut has been made, so that the cutter arm projects under the coal and the machine is ready to be 90 moved laterally to undercut the coal, the guiding part is rendered inoperative. This is done by disengaging the jack and moving the guiding device so that the shoe 12 is supported on the base 14 of the machine 100 (see Fig. 3). It will thus be seen that when not in use the guiding device is moved back into the frame of the machine, so that it is over a part of the machine, namely, the base 14, and under another part of the machine, as shown in Fig. 3. This guiding device is, therefore, a part of the machine, remains with the machine, and is entirely out of the way when not in use, so that it does not strike the coal as the 110

machine is moved laterally in doing its work. When it is desired to feed the machine laterally across the face of the coal, the power transmitting device 6 is moved 5 out to one side of the machine and fastened to a suitable fixed support, and the rotation of the drum 7 then causes the machine to move endwise.

A guard or safety device is arranged 10 to guard the chain, so that the operator cannot be injured thereby. In the drawing there is shown one form of guard for this purpose, consisting of the side pieces 45 and the connecting piece 46. This 15 connecting piece is provided with a suitable opening for the guiding part 11. This opening may be simply a hole through which the upper end of part 11 projects so that said part 11 and the shoe 12 will be connected with the guard through the connecting piece 46, and will cause said guard to move back into the machine as the machine moves forward to make its initial cut. This 20 connection is such that the shoe and part 25 11 may be removed when desired. This guard is arranged so as to slide back into the frame of the machine as the cutter chain is moved forward, as shown in Fig. 3. The side pieces 45 slide in guides 47 (see 30 Fig. 4). I provide the guiding part 11 with a pivoted latch 48, adapted to engage the cutter arm, so as to lock the guide and cutter arm together when it is desired to move the machine from place to place. The latch 35 48 is provided with an upwardly turned end 49, and the jack 13 has a beveled face 50 which engages the upturned end 49, so as to move the latch 48 to disengage the parts by the mere placing of the jack 13 in position. There is provided a series of guide 40 wheels, 51, for guiding the flexible power transmitting device 6, so that it may be led away from the machine in various directions.

45 When the cutters of the cutting chain are cutting the coal, and the feeding device is in operation, some suitable retarding device should be used to prevent the rear end of the machine from being fed forward too 50 rapidly, due to the fact that the resistance to the feed is at the forward end of the machine. Any suitable means for this purpose may be provided. As herein shown a flexible power transmitting device, 55, 55 passes over a drum, 52, and is connected to a fixed part, 53, located at a suitable point. A brake device, 54, is associated with the drum 52 to resist its rotation as desired to hold the machine in proper position when in operation.

60 When it is desired to move the machine about from place to place, the shoe 12 is moved up to the end of the cutter arm, as shown in Fig. 2, and the locking part 48 65 automatically engages the arm so as to lock

the shoe and arm against relative movement. The shoe then acts to hold the end of the cutter arm up so that neither it nor the cutters will be injured as the machine is moved about.

70 It will be seen that in this device the entire mining machine is moved forward to make the initial cut and is then moved laterally to make the rest of the cut, and that the cutter arm has two parts connected together at one end, namely, the parts 9 and 10, said parts being separated between their ends by a space, and that the cutter chain extends around the cutter arm, the outer faces of said parts engaging said cutter 75 chain so as to limit the inward movement of the opposite sides of the chain, there being a guiding device extending between the inner faces of said parts and adapted when in its operative position to hold the cutter 80 arm and chain against lateral movement.

85 It will further be noted that the part 9, for example, when the chain is arranged as shown in Fig. 1, resists the lateral pressure of the chain when cutting, and that the 90 guiding device engages the other side of the part 9 when the machine is making its initial cut so as to resist the lateral pressure of the arm.

95 I claim:

1. A mining machine comprising a cutter arm adapted to move longitudinally, and comprising two longitudinally extending substantially parallel beams connected together at one end and forming the main members of the cutter arm, said beams separated between their ends by a space, a cutter chain extending around the said cutter arm and movable with relation thereto, the outer faces of said beams engaging said chain so 100 as to limit the inward movement of the opposite sides of the chain, a guiding device extending between the inner faces of said beams and adapted when in its operative position to engage an inner surface thereof 105 to hold the cutter arm and chain against lateral movement.

110 2. A mining machine comprising a cutter arm adapted to move longitudinally and then laterally in making its cut, said cutter arm comprising two longitudinally extending substantially parallel beams connected together at one end and forming the main members of the cutter arm, said beams separated between their ends by a space, a cutter chain extending around said cutter arm and movable with relation thereto, the outer faces of said beams engaging said chain so 115 as to limit the inward movement of the opposite sides of the chain, a guiding device 120 extending between the inner faces of said beams and adapted when in its operative position to engage an inner surface thereof, to hold the arm and chain against lateral movement, said guiding device 125 movable 130

- with relation to said machine so that it may be moved to an inoperative position when the cutter arm is moving laterally.
3. A mining machine comprising a cutter arm adapted to move longitudinally and then laterally in making its cut, said cutter arm having a beam extending longitudinally therealong and forming one of the main members of the cutter arm, a cutter chain extending about said cutter arm and engaging the outer face of said beam when the arm is moving laterally, said beam resisting the lateral pressure of the chain when cutting, a guiding device projecting above and below said arm and engaging the other side of said beam when the cutter arm is moving longitudinally so as to resist the lateral pressure on the arm when the chain is cutting, said guiding device engaging the fixed surface beneath said cutter arm.
4. A mining machine comprising a cutter arm adapted to move longitudinally and then laterally in making its cut, said cutter arm comprising two beams extending longitudinally therealong, each of said beams provided at opposite sides thereof with flanges, a web intermediate said flanges and connecting them together, a cutter chain extending around said cutter arm and engaging the face of one of said flanges on each of said beams, the other flanges of said beams being opposed to each other and being separated by a space, a guiding device in said space between the latter flanges of said beams, said guiding device having a portion which engages the fixed surface under the cutter arm and means for connecting the other end of said guiding device with a fixed part so as to hold the guiding device stationary when the cutter arm is moved longitudinally.
5. A mining machine comprising a frame, a cutter arm connected therewith and provided with two guides separated by a space, a guiding device between said guides projecting above and below said guides and adapted to be fixed in position so as to permit the cutter arm to be moved forward but prevent its lateral movement, said guiding device separate from the frame, a support connected with said frame near the rear end of the cutter arm, upon which said guiding device is carried when not in use.
6. A mining machine comprising a frame, a cutter arm connected therewith, said cutter
- arm having a slot extending therealong, a shoe connected with said cutter arm so as to slide therealong and having a part projecting into said slot, means for automatically connecting the shoe with the front end of the cutter arm so as to prevent relative movement of the two.
7. A mining machine comprising a frame, a cutter arm connected therewith, a shoe connected with said cutter arm so as to slide therealong, means for automatically connecting the shoe with the cutter arm so as to prevent relative movement of the two, a device for exerting pressure on said shoe, adapted when in position to automatically disconnect the shoe from said arm.
8. A mining machine comprising a frame, a cutter arm connected therewith, a shoe adapted to engage the surface beneath said cutter arm, an upwardly projecting part connected with said shoe and engaging said cutter arm, a movable locking part connected with said upwardly projecting part and adapted to engage said arm and lock the shoe and arm together, a removable piece adapted to be connected with said upwardly projecting part and which, when placed in position, engages said locking part so as to automatically move it to an inoperative position.
9. In a mining machine, the combination of a movable bed frame, a cutter bar having a longitudinal slot rigid with the bed frame and projecting from the inner end thereof, a cutter chain supported on and guided by the cutter bar, a guide device adapted to extend through the slot of the cutter bar and be secured in position by engagement with the floor at its lower end and with the roof or coal face at its upper end, a draft rope, rotary mechanism on the bed frame co-operating with the draft rope to create a tension therein, said rope being adapted to be carried inward from the bed frame to a fixed abutment so that its tension will tend to advance the machine as an entirety longitudinally, and means on the bed frame for driving the cutter chain and the said rotary mechanism.
- Signed at Chicago, Illinois, this 15th day of September, A. D. 1910.
